UNITED STATES PATENT OFFICE.

GERHARDT F. SCHWARTZ, OF ST. LOUIS, MISSOURI.

AUTOMATIC CUT-OFF FOR GAS APPLIANCES.

Application filed October 28, 1922. Serial No. 597,568.

To all whom it may concern:

Be it known that I, GERHARDT F. SCHWARTZ, a citizen of the United States, and resident of St. Louis, in the State of Missouri, have invented certain new and useful Improvements in Automatic Cut-Offs for Gas Appliances, of which the following is a specification.

The present invention relates to improvements in automatic cut-offs for gas appliances and has for an object to provide for the closing of the gas control valve which regulates the supply of gas to the pilot burner, whenever the latter, for any reasons, becomes extinguished.

Other objects of the invention lie in the provision of coordinate parts and devices assembled in a relatively compact structure and cooperating in an efficient manner to secure the quick and positive closing of the pilot valve, to provide such parts as are adjustable to meet various conditions encountered in the structure and arrangement of different characters of automatic appliances and to enable the resetting of the parts with a greater facility than has been heretofore possible and to so construct and arrange the parts that casual closing of the valve is practically impossible.

The invention will be found to be of use particularly in connection with automatic gas appliances in general such as automatic gas water heaters, gas furnaces, gas steam boilers, radiators, gas stoves, etc. and the device accommodates itself to various positions of the pilot cut off valve encountered in these several appliances.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side view of a pilot burner, pipe and valve with the improvement shown in connection therewith.

Figure 2 is a fragmentary view of the vertical portion of the gas pipe showing the thermostat at substantially right angles to Figure 1, and

Figure 3 is a vertical section taken

through the horizontal portion of the feed pipe adjacent the control valve.

55

Referring more particularly to the drawings, 5 designates the pipe or tube conveying gas from an appropriate source of supply to the pilot tip or burner 6 and 7 represents the control valve situated in the horizontal portion of the pipe 5 and having the handle or operating arm 8 by which the valve is moved to an open or closed position and to regulate the quantity of gas flowing to the burner 6.

60

65

In accordance with the invention a thermostatic bar 9 is provided upon the vertical portion of the supply pipe and to cooperate with the trigger 10 pivoted at 11 upon the pipe or a suitable support and being made with the recessed shoulder 12 at one side to receive the free lower end of the thermostat, which may be made from a strip of brass metal amalgamated to a strip of steel. The upper end of the thermostatic bar 9 is received between the flanges 13 bent radially from a collar 14 clamped about the supply pipe beneath and adjacent the burner tip 6. This sleeve may be of cast brass or other material found appropriate for the purpose and the flanges and the portion of the bar 9 lying therebetween are secured together by the screws or other fastenings 15.

70

75

The trigger 10 is made with a projection 16 extending oppositely to the shoulder 12 and having a notched upper portion to receive and retain the loop 17 upon the end of the cord or flexible element 18. This element is employed to sustain the weight 19 provided to close the valve 7 and the weight

80

85

is particularly connected to an end of the flexible element just after passing slidably through the opening 20 made in the valve handle 8. The cord carries a button or stop 21 fixed thereon and normally lying spaced an appreciable distance above the valve handle as for instance shown in Figure 1 and suitably below a grooved wheel or pulley 22 over which the cord 18 is trained.

90

The pulley 1 is supported in the bracket 23 having a sleeve 24 embracing the horizontal portion of the pipe 5 and being secured thereto as by the fastening 25.

95

Now in the operation of the device, the burner 6 being lighted with the valve 7 in the open condition wherein it is shown in

100

105

Figure 1, the thermostatic bar 9 is heated and in this condition warped into contact with the trigger 10, its free end lying engaged in the recessed shoulder 12. The loop 17 is engaged with the projection 16 and the weight 19 is suspended with the valve arm 8 in the raised horizontal position.

Should the flame however become extinguished accidentally the thermostatic bar 9 will warp, under the cold condition, to the left or dotted line position shown in Figure 1, thus removing its free end from engagement in the recessed shoulder 12 of the trigger. Under circumstances shown in the full line position, the weight will be prevented from rotating the trigger about its axis 11 due to the direct thrust of the bar 9 but when this obstacle is removed as occurs under the conditions just stated the weight 19 will be released and it will consequently rotate the trigger in a clockwise direction, freeing the loop 17, so that the weight normally held in the potential position by this set arrangement of the parts, will be free to descend and to carry with it the cord 18 and the connecting button or stop 21. Now the stop is sufficiently large to avoid its passing through the opening 20 in the valve handle 8, which it therefore strikes. The button being initially spaced above the valve handle, will permit of the weight acquiring a considerable momentum before any connection between the weight and the valve arm is established. This is desirable for the reasons that the valve sometimes sticks and the valve handle is only turned by the application of considerable force which the dormant condition of the weight could not dislodge.

The button or stop acted on by the weight will swing the arm 8 downwardly with the weight until the valve 7 is tightly closed and the flow of gas completely shut off. The construction above described is particularly advantageous as it admits of the relighting of the pilot and the restoration of the trigger, thermostat and weight to the locked and initial condition. The device has the further advantage that the clamp collar 24 may be adjusted along the pipe 5 near to or further from the trigger but may be situated relatively to the valve wherever this may occur in various structures and by the simple expedient of varying the cord 18 to suit the new conditions, the device may be applied and adjusted to any of the

known forms of gas appliances and without needing a particular construction in the water heater itself.

It is obvious that various changes and modifications may be made in the details of construction and design of the above specifically described embodiment of this invention without departing from the spirit thereof, such changes and modifications being restricted only by the scope of the following claims:

What is claimed is:

1. In a gas control for automatic appliances, the combination of a pilot burner, a valve for controlling the supply of gas to the burner, valve-closing means, a movable trigger, a flexible connection adapted to detachably engage the trigger and connected to the valve closing means for normally holding the latter in a potential condition, and a thermostat placed relatively to the burner and when heated in the path of movement of the trigger for preventing the movement of the trigger and the valve-closing means, said thermostat adapted to warp out of engagement with the trigger when cold and permit movement of the same.
2. In a gas control for automatic appliances, the combination of a pilot burner, a valve for controlling the supply of gas to the burner, weight means for closing said valve, a rotary trigger, a flexible connection having releasable engagement with the trigger for normally holding the weight elevated, and a thermostat placed relatively to the burner and releasably engaging the trigger in the heated condition of the thermostat.
3. In a safety control for automatic gas appliances, the combination of a pilot burner, a valve for controlling the supply of gas to the burner, a weight for closing said valve, a flexible connection carrying said weight and having means for acting upon the valve only after the weight has acquired momentum, a movable trigger releasably engaging said flexible connection to hold the weight suspended and a thermostat engaging in the heated condition said trigger but adapted to react when cold and disengage the trigger to enable the weight to fall.

In testimony that I claim the foregoing as my invention, I have signed my name hereunder.

GERHARDT F. SCHWARTZ.
